WILLIAM G. KAISER, OF FORT WAYNE, INDIANA, ASSIGNOR OF ONE-HALF TO CHARLES B. BOWEN.

TOP-BOW CLAMP.

1,249,634.

Specification of Letters Patent. Patented Dec. 11, 1917.

Application filed March 19, 1917. Serial No. 155,657.

To all whom it may concern:

Be it known that I, WILLIAM G. KAISER, a citizen of the United States of America, and resident of Fort Wayne, in the county of Allen and State of Indiana, have invented 5 certain new and useful Improvements in Top-Bow Clamps, of which the following is a specification.

This invention relates to improvements in 10 top bow clamps of that class used for supporting and securing automobile tops when collapsed. The object of the improvement is to so construct the device that its securing hook will automatically move out of the 15 path of the bows when released and thus allow the top to be raised and lowered quickly and without interference by the securing means.

The object of the invention is accomplished 20 by the construction illustrated in the accompanying drawings in which:

Figure 1 is an elevation of the device in central section;

Fig. 2 is an elevation of the movable hook 25 member;

Fig. 3 is an elevation of the device shown in a plane at right angles to that of Fig. 1;

Fig. 4 is a detail view showing a cross-section of Fig. 2 on the line $x-x$;

Fig. 5 is a detail view showing a cross-section of Fig. 1 on the line $y-y$, the 30 springs being omitted;

Fig. 6 is a plan view of the yoke;

Fig. 7 is an elevation of the yoke projected 35 from Fig. 6;

Fig. 8 is a plan view of the yoke applied to the hook-member, the section being the same as Fig. 4;

Fig. 9 is an elevation of the spring for actuating 40 the hook-member;

Fig. 10 is a bottom plan of the spring shown in Fig. 9; and

Fig. 11 is a cross-section of Fig. 1 on the line $z-z$ thereof.

Similar characters of reference indicate 45 corresponding parts throughout the several views and having reference now to the same:

1 is a hollow bracket casting having bearings 2 and 3 in its upper portion for guid-

ance of the hook member 4 that is arranged in the bracket to have both vertical reciprocating and turning movement therein. The bracket has also a laterally projecting chambered extension 5 in which is secured a 55 spring supported rest 6, there being a coil spring 7 contained within the extension that acts upwardly against the rest. The hollow extension has a series of openings 8 in its upper face adapted for the entrance 60 therethrough of a corresponding series of lateral projections 9 on the lower end of the rest, the purpose being to permit the introduction of the extending lower portion of the rest into the extension, so that the rest 65 after its introduction may be turned to normal position against the pressure of the spring 7 and be secured in the extension. The lateral projections 9, bear upwardly 70 against the inner face of the extension 5 at points between the openings 8 therein and prevent unintentional dislodgment of the rest when normally positioned. Also, from the inner face of the extension extend pendant lugs 10 between which one of the projections 9 normally extends and prevents the rest from being turned far enough to admit of its withdrawal from the extension 5 when held by the spring in its uppermost 75 position. The movable hook-member 4 has 80 in its overhanging portion 11 a cushion 12, and the upper face of the rest 6 has a covering of leather 13, the intention being to hold the bows of the top (not shown) between the leather faced rest and the cushioned hook so as to eliminate scuffing of the bows 85 at the respective contact points.

The hook-member 4 has two series of ratchet-teeth 14 and 15 respectively. The edges of the teeth of one series coincide with 90 the edges of the corresponding teeth of the other series, and the two series of teeth also extend in planes at right angles to each other.

A throat 16 is made in the shank of the 95 hook-member at a point beneath the ratchet-teeth, the lower webbed portion 17 of the shank being united with the upper portion by the eccentric neck 18. A yoke 19 having a recess 20 made therein is adapted to extend 100

into the throat and fit in the neck so that its periphery will be concentric with the stem of the hook-member. The actuating spring 21 has a vertical extension 22 formed at its upper end adapted to fit into the outer portion of the recess 20 in the yoke, and the lower end of the spring is formed with a flat extension 23 so as to fit in the socket 24 correspondingly shaped in the lower end of the bracket 1. By thus forming the spring 21 its lower end is anchored so that it cannot turn in the socket, while its upper end has connection with the yoke so that torsional strain is applied to the spring when the hook-member is manually turned to securing position. The spring 21 also acts upwardly against the yoke 19 and thus forces the hook-member to its uppermost position when released. The yoke serves also as a stop to limit the upward movement of the hook-member by coming into contact with the lower face of the bearing 3.

A sliding ratchet 25 extends horizontally into an opening 26 made in the bearing 3 and is adapted to engage the teeth of one or the other of the series of ratchet-teeth 14 or 15 accordingly as the hook member is turned. The outer end of the ratchet has a knob 27 by means of which the ratchet-member may be pressed from engagement with the teeth. A spring 28 acts against the ratchet and holds it normally in engagement with the teeth of the hook-member. The drift of the teeth 14 and 15 are such when engaged by the ratchet, that the hook-member may be forced downwardly but will be prevented by the ratchet from retracting until released.

The bracket 1 may be attached to the side of the vehicle in any suitable manner. For instance: The bracket may have a perforated lug 29 with a set-screw 30 for attachment to a stud (not shown) that is ordinarily provided on automobiles for the purpose.

In using the device the hook-member is turned so that its overhanging portion will extend out of the path of the bows, thus allowing the latter to be lowered onto the rest 6. The hook-member is then turned outwardly and forced downwardly so that the bows are held between the rest 6 and the overhanging portion of the hook. By applying downward pressure to the bows and hook-member at the same time, the spring 7 is made to yield somewhat and the ratchet is admitted into the teeth 14 successively as the hook-member is lowered. When manual pressure is withdrawn from the bows, they are held upwardly against the overhanging portion of the hook by the spring-pressed action of the rest and are thereby prevented from rattling.

When it is desired to release the bows as in raising the top, the ratchet is disengaged

from the hook-member by applying pressure to its knob whereupon the hook-member thus released will be forced upwardly and also turned by the expansion and torque actions of the spring 21. Thus, the bows may be raised without interference of the hook-member.

The shank of the hook-member may be slightly enlarged at its upper end as indicated at 31 so that it will fit snugly in the upper bearing of the bracket when the hook-member is forced down into idle position. This will have the effect of preventing rattling vibrations of the hook-member in the bracket.

What I claim is:—

1. In a device of the class described, a hollow bracket having bearings in its upper portion, and a lateral hollow extension at its base; a hook-member having vertical and turning movement in said bracket and having an overhanging portion at its upper end, the shank of the hook-member having made therein two adjacent series of ratchet notches extending respectively in planes at right angles to each other; a yoke secured on the stem of the hook-member adapted to limit the upward play thereof; a spring secured at its lower end against turning movement in the lower end of the bracket and also having connection with the yoke at its upper end so as to be turned thereby, said spring being also adapted to bear upwardly against the yoke; a ratchet in the bracket adapted to engage the teeth of one series or the other accordingly as the hook-member is positioned; and a spring supported rest secured in the lateral extension of the bracket.

2. In a device of the class described, a bracket; a hook-member having vertical and turning movement in the bracket, the stem of the hook-member having a series of ratchet-teeth made therein; a yoke secured on the stem; a ratchet in the frame adapted to engage the teeth in the stem; a spring secured at its lower end against turning in the bracket and having connection at its upper end with the yoke so as to turn therewith; and a rest yieldingly supported at the lower portion of the bracket.

3. A bracket having a rest at its lower end; a hook-member having vertical and turning movement in the bracket; a spring secured in the bracket and being adapted to actuate the hook-member vertically and turn the same out of securing position; and ratchet mechanism for holding the hook-member in securing position.

4. In a device of the class described, a bracket having a lateral extension at its lower end; a yieldingly supported rest secured in the extension; a hook-member having vertical and turning movement in the

bracket, the shank of which has ratchet-teeth made therein; a ratchet for engaging the teeth and holding the hook-member in adjusted positions; and a spring acting to move the hook-member vertically and turn the same out of securing position.

In testimony whereof I affix my signature in presence of two witnesses.

WILLIAM G. KAISER.
